UNITED STATES PATENT OFFICE.

WALTER BREWITT, OF ESSEN-ON-THE-RUHR, GERMANY.

APPARATUS FOR USE IN BUTT-WELDING THE ENDS OF RAILS.

1,088,006.

Specification of Letters Patent.

Patented Feb. 24, 1914.

Application filed September 14, 1911. Serial No. 645,335.

To all whom it may concern:

Be it known that I, WALTER BREWITT, a subject of the King of Prussia, German Emperor, and resident of Essen-on-the-
5 Ruhr, in the German Empire, have invented a new and useful Apparatus for Use in Butt-Welding the Ends of Rails, of which the following is an exact specification.

This invention refers to an improvement 10 in apparatus for alining and drawing together rail ends to be butt-welded.

It is old to aline rails by means of guides lying along the heads of the rails, and by means of clamp devices accurately secured 15 to the rail-heads. If used for instance with grooved rails, projections shaped to fit the groove were provided on the guide devices. This arrangement was chiefly intended for use with straight rails, and for curved rails 20 different guides were necessary for curves of different radii.

Now the present invention consists in making provision for enabling the clamping and guiding device to be used with curved 25 rails. According to this invention the guides are so constructed that they may be easily engaged with a rail of any curvature in order to aline the rail tread in the vertical direction. The horizontal alinement of the 30 rails is produced however by fixed and movable projections or recessed members which are connected to the guides in a manner corresponding to the curvature of the rails.

In order to enable the invention to be 35 readily understood reference is made to the accompanying drawings in which:

Figure 1 is a transverse section of the new or improved apparatus attached to grooved rails the section being taken upon 40 the line A—B of Fig. 2, but showing the eccentric with its projection in side elevation. Fig. 2 is a plan view of a part of the device. Fig. 3 is a side and plan view of the guide. Fig. 4 is a diagrammatic plan view of the whole device.

Referring to the drawings s s_1 indicate the rail ends, m m_1 the yokes or saddles mounted on the rail heads, n the ordinary clamps, i the special clamp, the bolt i_1 of which 45 is adapted to force down into the groove of the rail a wedge or tongue, d d_1 the guide rods passing through sleeves in the yokes or 50 saddles m m_1 and fitted with nuts f , and l the guide plate or bar adapted to lie along the rail head and to engage the latter.

Now according to these improvements the

guide bar l instead of engaging the rail for a considerable distance as by means of a rib, is, in the case of a grooved rail, provided with a finger or projection o at one end and 60 near the opposite end is formed with a hole r in which is inserted a revoluble plug or disk p formed or provided with an eccentric pin q which may be turned by suitable means as for example by the square head 65 shown.

It will now be understood that upon the yokes or saddles being applied to the rail ends s s_1 and fixed by the clamps n i , the projection or finger o on the guidebar or plate 70 l lies in the groove of the rail and the disk or plug p is adjusted so that its projection q also lies in the groove in such relation with the projection o as suits the curve with which the rails are to conform. These projections thus fix the lateral direction of the rail ends s s_1 while the latter are being drawn together owing to the turning of the nuts f which results in the saddles m m_1 being moved along the rods d d_1 .

It will be seen that the disk or plug p p_1 of each of the saddles or yokes m m_1 can be turned so as to move the corresponding projection q q_1 into such relative positions as will suit right or left handed curves of different radii as will be readily understood by reference to Fig. 4. Or the projection can be moved to a middle position to suit straight rails. A scale and indicator may be provided for indicating the proper adjustments to be made for the different curves. For example a circular scale may be provided as shown in Fig. 2 upon the plate l around the hole r and any suitable indicator or indicating point on the plug p 95 may be used in conjunction with the scale. In Fig. 2 an arrow is indicated for this purpose. If the plug p be turned after the projection has been engaged with the groove in the rail head, the rail will be adjusted 100 to the true position of coincidence with the curve which it is desired to give to the track.

What I claim is:

1. In an apparatus for alining the ends of curved rails, the combination with a frame, 105 of alining means and clamping devices, said alining means having a guide provided at separated points lengthwise of the rail with projections adapted to engage a longitudinal curved surface of the rail, at single 110 points in the length of said rail.

2. In an apparatus for alining the ends of

- curved rails, the combination with a frame, of alining means and clamping devices, said alining means having a guide provided at separated points lengthwise of the rail with 5 projections adapted to engage a longitudinal curved surface of the rail at single points in the length of said rail and one of which is movable relatively to the other.
3. In an apparatus for alining the ends of 10 curved rails, the combination with a frame, of alining means and clamping devices, said alining means having a guide provided at separated points lengthwise of the rail with 15 projections constructed to engage a longitudinal curved surface of the rail and one of which is movable relatively to the other crosswise of the rail.
4. In an apparatus for alining the ends of 20 curved rails, the combination with a frame, of alining means and clamping devices, said alining means having a guide provided at separated points lengthwise of the rail with 25 projections adapted to engage a longitudinal curved surface of the rail at single points in the length of said rail and one of which is movable relatively to the other lengthwise of the rail.
5. In an apparatus for alining the ends of 30 curved rails, the combination with a frame, of alining means and clamping devices, said alining means having a guide provided at separated points lengthwise of the rail with 35 projections constructed to engage a longitudinal curved surface of the rail and one of which is movable relatively to the other both lengthwise and crosswise of the rail.
6. In an apparatus for alining the ends of 40 curved rails, the combination with a frame, of alining means and clamping devices, said alining means having a guide provided at separated points lengthwise thereof with 45 rail-engaging projections located in different positions crosswise of said guide, and adapted to engage the rail at single points in the length thereof.
7. In an apparatus for alining the ends of 50 curved rails, the combination with a frame, of alining means and clamping devices, said alining means having a guide provided at separated points lengthwise thereof with rail-engaging projections of small areas located 55 in different positions crosswise of said guide, and adapted to engage the rail at single points in the length thereof.
8. In an apparatus for alining the ends of 60 curved rails, the combination with a frame, of alining means and clamping devices, said alining means having a guide provided at separated points lengthwise thereof with a pair of rail-engaging projections of small areas one of which is movable to different positions crosswise of said guide.
9. In an apparatus for alining the ends of 65 curved rails the combination with a frame, of alining means and clamping devices, said alining means having two guides each of which is provided at one end with a fixed 70 projection and at the other end with a movable projection both adapted to engage the rail.
10. In an apparatus for alining the ends of 75 curved rails the combination with a frame, of alining means and clamping devices, said alining means having two guides each of which is provided at one end with a fixed 80 projection and at the other end with a movable projection both adapted to engage the rail, the latter projection being movable eccentrically in a hole of said guide.
11. In an apparatus for alining the ends of 85 curved rails the combination with a frame, of alining means and clamping devices, said alining means having two guides each of which is provided at one end with a fixed projection and at the other end with a movable projection both adapted to engage the rail, said movable projection being eccentrically arranged on a plug or disk rotatable in a hole of said guide.
12. In an apparatus for alining the ends of 90 rails, the combination with a frame, of alining means and clamping devices, said alining means having a guide which is provided at separated points lengthwise of the rail with 95 projections one of which is movable crosswise of the guide to such an extent as to permit it to be brought into alinement with the other on a straight rail or shifted into position for coöperation with a curved rail.
13. In an apparatus for alining the ends of 100 rails, the combination with a frame, of alining means and clamping devices, said alining means having two guides each of which is provided at separated points lengthwise of the rail with 105 projections one of which is movable crosswise of the guide to such an extent as to permit it to be brought into alinement with the other on a straight rail or shifted into position for coöperation 110 with a curved rail.
